(57) **CLAIM**

The ornamental design for a microphone, as shown and described.

DESCRIPTION

FIG. 1 is a front, top, and right side isometric view of a microphone depicting our new design;

FIG. 2 is a rear, bottom, and left side isometric view of the microphone depicted in FIG. 1;

FIG. 3 is a front elevation view of the microphone depicted in FIG. 1;

FIG. 4 is a rear elevation view of the microphone depicted in FIG. 1;

FIG. 5 is a top plan view of the microphone depicted in FIG. 1;

FIG. 6 is a bottom plan view of the microphone depicted in FIG. 1;

FIG. 7 is a right side elevation view of the microphone depicted in FIG. 1; and,

FIG. 8 is a left side elevation view of the microphone depicted in FIG. 1.

1 Claim, 8 Drawing Sheets
